BURIAL COUCH COVER

Kenneth S. Conley, Nashville, Tenn., assignor to Cross
Mausoleum and Funeral Home, Inc., Nashville, Tenn.

Filed July 29, 1970, Ser. No. 24,207

Term of patent 14 years

Int. Cl. D31

U.S. Cl. D19—1

FIG. 1 is a side elevational view of a burial couch cover, showing my new design;

FIG. 2 is a top plan view; and

FIG. 3 is an end elevational view, the opposite end being substantially a mirror image thereof.

I claim:

The ornamental design for a burial couch cover, as shown and described.
